US00D604429S

(12) **United States Design Patent**
McCarthy et al.

(10) **Patent No.:** **US D604,429 S**
(45) **Date of Patent:** **** Nov. 17, 2009**

(54) **STAINED GLASS**

(75) Inventors: **Jessica Marie McCarthy**, Belton, TX
(US); **Amanda Peeler**, San Diego, CA
(US)

(73) Assignee: **JELD-WEN, Inc.**, Klamath Falls, OR
(US)

(**) Term: **14 Years**

(21) Appl. No.: **29/303,572**

(22) Filed: **Feb. 12, 2008**

(51) **LOC (9) Cl. 25-01**

(52) **U.S. Cl. D25/103**

(58) **Field of Classification Search** D25/103-111,
D25/52, 48, 138; D6/306, 470, 494; D26/122;
D21/494; 428/38, 49, 426, 542.2, 542.4,
428/542.6; 52/204.59

See application file for complete search history.

Primary Examiner—T. Chase Nelson*Assistant Examiner*—Anhdao Doan(74) *Attorney, Agent, or Firm*—Stoel Rives LLP(57) **CLAIM**

The ornamental design for a stained glass, as shown and described.

DESCRIPTION

FIG. 1 is an elevation view of a stained glass of the present invention; and,

FIG. 2 is a perspective view thereof.

The broken lines in the drawings depict environmental subject matter and form no part of the claimed design.
